UNITED STATES PATENT OFFICE

127,563

DESIGN FOR A RACK FOR GLASSES OR THE LIKE

Ellery J. Cloutier, Muskegon, Mich., assignor to
The Brunswick - Balke - Collender Company,
Chicago, Ill., a corporation of Delaware

Application April 7, 1941, Serial No. 100,190

Term of patent 14 years

To all whom it may concern:

Be it known that I, Ellery J. Cloutier, a citizen of the United States, residing in the city of Muskegon, county of Muskegon, State of Michigan, have invented a new, original, and ornamental Design for a Rack for Glasses or the like, of which the following is a specification, reference being had to the accompanying drawing, forming a part thereof.

Figure 1 is a perspective view of a rack for glasses or the like, showing my new design;

I claim:

The ornamental design for a rack for glasses or the like, as shown.

ELLERY J. CLOUTIER.
